ELECTRIC HAMMER

Robert T. Fetherston, Milwaukee, Wis., assignor to Milwaukee Electric Tool Corporation, Milwaukee, Wis., a corporation of Wisconsin

Application July 24, 1936, Serial No. 92,309

4 Claims. (Cl. 125—33)

This invention relates to portable percussion tools such as electric hammers.

In such tools the driving motor must ordinarily be of the type requiring a commutator. The motor runs at very high speeds in order to provide the necessary power with light weight, and at each blow of the hammer there is transmitted to the body of the tool and to the motor a severe jar or shock. This shock results even during normal operation, and at times is greatly increased when the ram overruns, for any of various reasons, and strikes the end of the chamber in which it reciprocates. Any such repeated jar or shock is seriously detrimental to the operation of the motor commutator, causing sparking and undue wear, together with the loss of power in heating, and various other objectionable results. Similarly the vibration and shock is detrimental to various other parts of the device including the switch. It is very objectionable to the hand of the operator who guides the tool. Also it tends to loosen all the bolts, screws or rivets etc. holding the various parts together. Moreover the repeated blows tend to build up the amplitude of vibration, unless prevented, thereby aggravating the various objectionable results mentioned.

An object of the invention is to provide a structure which will reduce the jar or shock of individual blows on the body of the tool and parts thereof, without reducing the effectiveness of the hammer blow on the work, and will damp the recurrent vibrations to prevent their building up vibrations of increasing amplitude.

The invention consists in the construction shown, described, and claimed herein, and in such variations or modifications of the structure shown and described as may be equivalent to the structure of the claims.

Like reference characters apply to the same parts throughout the specification, and in the drawing:

Figure 1 is a perspective view partly in section of a portable electric hammer incorporating the invention.

Figure 2 is a longitudinal section of the same device.

Figure 3 is a modified hammer structure also incorporating the invention.

The machine as shown in Figs. 1 and 2 includes a plurality of housings generally denoted by the numerals 1 and 2. The housing 1 is provided with a hand grip portion 3 in which is housed a switch 4 having a trigger-like operating member 5. Cables 6, 7 lead from the switch to a motor, 55 carried by housing 1, generally denoted by the

numeral 8, which is of high speed, series wound type having a rotor 9 and a commutator 10 for supplying current to the rotor, there being commutator brushes such as 11 retained in the usual or any suitable manner in brush holders such as 12, to be spring pressed against the commutator.

Housing 1 also carries reduction gearing including the pinion 13 carried by an extension of the motor shaft and a gear 14 fixed on a shaft 15.

End plates 16, 17 of housing 1 carry the bearings for pinion 13 and shaft 15, and are removably fixed with the main casting 18 in part by the means of screws such as 19 and in part by the bolts 20, 21 which extend through suitable flanges 45 at the adjacent ends of housings 1 and 2 to fasten the housings together, there being another bolt 22 which does not extend through.

The housing 2 carries a shaft 23 coaxially aligned with the shaft 15 and coupled to be driven from shaft 15 by a member 24. At its other end the shaft 23 carries a cam element 25 against which a cam member 26 is continuously pressed by a spring 27, the spring seating at the one end on an abutment member 28 fixed with housing 2, and seating against the cam member 26 at its other end.

Cam member 26 is fixed with a reciprocating hammer member 29. At the end of the housing 1 is fixed a tool receiving socket or member 30 providing a bore 31 through which the shank of a tool such as 32 may extend to be struck by the reciprocating member 29.

During revolution of shaft 23 from the motor 8 through the mechanism described the cam element 25, revolving against a cam face 33 of the cam member 25, presses the member 26 and the reciprocating member 29 to the right of Fig. 2 against the resistance of spring 27. The cam member 26 is of a form such that after traveling 40 to the right the reciprocating member 29 is suddenly released to be thrust to the left in Fig. 2 by the spring, thereby delivering a hammer blow against the end of the tool retained in the socket or bore 31. At times, and particularly if there is not sufficient resistance to the tool the member 29 may overrun to strike the interior face of the member 30. The speed of the motor and the driving connections to the shaft 27 are such as to deliver a great many of such blows per minute 50 at substantially equal intervals.

The shock and vibration incidental to the release of the member 26, and to the striking of the member 29 against the end of the tool or against member 30 are, unless prevented, transmitted to 55

the housings 1 and 2 and to each of the various elements of the device. Unless prevented, such vibrations cause sparking between the brushes 11 and commutator 10 of the motor 8 and the various other objectionable results previously mentioned, particularly if the vibrations tend to be amplified or built up by the timed repetition of the hammer strokes.

To reduce the shock of individual blows and 10 to prevent the building up of the amplitude of the vibration caused by repeated blows, there is provided the following structure. A member or gasket 35 of suitable shock absorbing and vibration damping material such for instance as rubber 15 is interposed between the adjacent end faces of the housings 1, 2, the bolts 20, 21, 22 passing through the gasket. In addition, underneath the heads of each of the bolts 20, 21, 22 there are 20 additional gasket or washers of the shock absorbing or resilient material, such as 36, 37, 38. The bolts 20, 21, 22 are seated solidly against the end plate 17 of housing 1, whereby to effect a predetermined space underneath the bolt heads of such value as to provide a predetermined initial 25 compression of the shock absorbing material of the several gaskets. By the means of the described construction each of the housings 1, 2 is cushioned on shock absorbing and vibration damping material in either direction of its movement, set up by the hammer operation, relative 30 to the other housing and each of the housings and every part carried thereby is effectively cushioned against individual blows and the structure is such as to provide effective damping against 35 building up of vibration effects by repeated blows. In order to provide added surface bearing against the washers 36, 37, 38 the bolts 20, 21, 22 are each provided with washers or bearing plates such as 39, 40 shown in Fig. 2 for the bolt 22.

40 The effect of the shock absorbing and vibration damping mounting as described is to substantially completely prevent the sparking between the commutator 10 and brushes 11 of the motor and to provide for the brushes and commutator substantially the same life as would be obtained in a tool which was not subjected to the shock of the hammer blows, and to greatly increasing the efficiency and power of the motor, and to greatly reduce the tendency of the motor 45 and its commutator to overheat. There is also a material reduction in the shock and vibration transmitted to the hand of the operator, and substantially no tendency for the switch and various fastenings to be loosened or damaged.

55 It is to be understood that the gaskets, as here shown may be made of various materials, and in some instances some or all of the gaskets may be replaced with springs of suitable form and position.

60 The hammer shown in Fig. 3 includes a motor, not shown, having commutators as indicated at 41 and housed within a casing 42, there being a pinion 43 fixed on the motor shaft and engaging a gear 44 having fixed thereon an eccentric 65 45 which reciprocates a crank 46. Fixed with crank 46 is a rod 47 which reciprocates a plunger or hammer member 48, guided in a housing 49, the member 48 being cushioned in either direction by springs 50, 51. Carried at the lower end 70 of member 48 is an anvil or hammer 52 positioned to strike the end of a tool 53 at each reciprocation of crank 46, the tool being removably retained in a member 53a.

At the joint between the member 53a and housing 49 there is provided a resilient gasket,

and resilient washers 55, 56 associated with the bolts 57, 58 in a manner and for a purpose and result similar to the resilient gasket 35 and washers 36, 37 of the hammer shown in Figs. 1, 2.

The motor housing 42 and housing 49 are removably fixed together at a joint indicated at 54, and it is also contemplated that such joint may, if desired, be provided with resilient gaskets and washers (not shown) such as those shown for joining the motor and hammer housings 1, 2 of Fig. 1, and for joining the member 53a and housing 49 of Fig. 3.

With the structure disclosed any shock which tends to move one of the housings 1, 2 relative to the other primarily further compresses one of the opposed resilient devices consisting respectively of the gasket 37 and of the collective gaskets 36, 37, 38. The other resilient device is simultaneously relieved of some of its initial compression set up by the bolts 20, 21, 22. This cushions the shock and, in addition, a considerable portion of the force of the blow is absorbed or damped out by the deformation of the resilient devices and, in part by movement of one or both of the housings 1, 2. Such rebound as occurs from a shock in the one direction is similarly cushioned and damped by the corresponding but opposite action of the resilient devices in the other direction, and the result of the combined damping of both the initial and rebound shocks is to substantially completely cushion and damp out any individual shocks irrespective of the rate at which they may be repeated, and to entirely prevent any building up or amplification thereof which might otherwise occur for shocks repeated at regular intervals.

What is claimed is:

1. In a portable percussion tool, the combination of a reciprocatory percussion element, a motor connected for operation of said element, a 40 housing for said hammer element, a housing for said motor adjacent said element housing, said housings having adjacent faces along a plane transverse to the path of reciprocation of said element, a shock absorbing and vibration damping gasket interposed between said housings, bolts extending through said gasket for removably fixing said housings together, and another shock absorbing and vibration damping gasket associated with some of said bolts, both of said 45 gaskets being simultaneously compressed by the tightening of said bolts to fix the one housing with the other.

2. In a percussion tool providing a hand-grip portion at the one end and a tool receiving socket 55 at the other end, the combination of a motor, a reciprocable hammer element adjacent said socket end and adapted to deliver percussion blows against a tool held in said socket, a transmission connecting said motor for reciprocation 60 of said hammer element, a frame housing said hammer element and transmission and providing separable portions having faces adjacently arranged relative to a plane transverse to the path of reciprocation of said element, a shock absorbing and vibration damping member interposed between said faces, means fixing said housing portions together and simultaneously compressing said member to receive thrust of one of said housing portions in one direction, and another shock absorbing and vibration damping member compressed by said means and positioned to receive the thrust of the last mentioned housing portion in the other direction.

3. In a percussion tool the combination of a 75

housing providing a hand grip at the one end thereof, a reciprocable percussion element having a portion exposed at the other end of said housing, said housing including portions having adjacent faces along a plane transverse to the path of reciprocation of said element and between said hand grip and the exposed portion of said element, a shock absorbing and vibration damping gasket interposed between said adjacent faces 5 for compression by forces tending to reduce the spacing of said faces, and another shock absorbing and vibration damping gasket adapted for compression by forces tending to increase the spacing of said faces.

10 4. In a percussion tool the combination of a housing providing a hand grip at the one end thereof, a reciprocable percussion element hav-

ing a portion exposed at the other end of said housing, said housing including portions having adjacent faces along a plane transverse to the path of reciprocation of said element and between said hand grip and the exposed portion of said element, a bolt continuously urging the one 5 of said housing portions in the direction of the other, and shock absorbing and vibration damping gasket means including a gasket portion interposed between said faces for compression by forces tending to reduce the spacing of said faces and another gasket portion associated with said bolt for compression by forces tending to increase the spacing of said faces, each of said gasket portions being simultaneously compressed by said 10 bolt.
